(57) **CLAIM**

The ornamental design for a sprinkler, as shown and described.

DESCRIPTION

FIG. 1 is a front elevational view of a sprinkler according to the invention;

FIG. 2 is a bottom plan view of the sprinkler of FIG. 1;

FIG. 3 is a top plan view of the sprinkler of FIG. 1;

FIG. 4 is a left side elevational view of the sprinkler of FIG. 1, the right side elevational view being identical;

FIG. 5 is a front elevational view of an alternate embodiment of the sprinkler of FIG. 1;

FIG. 6 is a perspective view of the sprinkler of FIG. 1, with the mounting environment of the sprinkler illustrated in phantom; and,

FIG. 7 is a perspective view of the alternate sprinkler embodiment of FIG. 5, also with the mounting environment illustrated in phantom.

The broken line showing is for illustrative purposes only and forms no part of the claimed design.

1 Claim, 3 Drawing Sheets
